UNITED STATES PATENT OFFICE.

FRED JUDGE, OF HASTINGS, ENGLAND.

CAMERA FOR COMPOSITE HELIOCHROMY.

1,312,694.

Specification of Letters Patent.

Patented Aug. 12, 1919.

Application filed October 17, 1916. Serial No. 126,126.

To all whom it may concern:

Be it known that I, FRED JUDGE, a subject of His Majesty King George V of the United Kingdom of Great Britain and Ireland and of the British Dominions Beyond the Sea and Emperor of India, residing at Hastings, Sussex, England, have invented certain new and useful Improvements in Cameras for Composite Heliochromy, of which the following is a specification.

The present invention relates to improvements in semi-automatic cameras of the type wherein color sensitive surfaces are carried on a step-wise rotating carrier of disk form, which carrier rotates by part circle stages behind the lens so as to successively expose the separate color sensitive surfaces.

By the present invention is provided a semi-automatic heliochromic camera for multiple or composite heliochromy in which a single color sensitive plate, or the equivalent of a single plate is on a step-wise rotating disk like carrier behind the lens; the invention being characterized in that the carrier is a face plate like the face plate of a lathe and is integral with a spindle like the mandrel of a lathe; this arrangement conducing to steadiness of action.

An embodiment of the invention as actually constructed and found to work well is figured in the accompanying drawings in which:

Figures 1 and 2 show two systems of plotting or apportioning the sensitive surface or plate for exposure.

Fig. 3 is a plan view of a camera, constructed according to this invention.

Fig. 4 is a front sectional view of the camera on the line $y-y$ of Fig. 3.

Fig. 5 shows the color screen disk.

Fig. 6 shows a roll film system mounted on the carrier for the sensitive surface.

Fig. 7 is a section on $x-x$ Fig. 3 with aspect toward the right.

Figs. 8 and 9 show the locking disk and locking pin respectively for controlling the step-wise rotation of the carrier for the sensitive surface.

Figs. 10 and 11 are front view and part sectional view on line 10 $\circ$ -10 $\circ$, Fig. 10, respectively to a reduced scale of the camera box with the mandrel spindle and allied parts removed.

Fig. 12 is a front view, and Fig. 13 a side view of the disk for driving the color screen disk.

Fig. 14 is a front view and Fig. 15 a side view of the disk controlling the locking pin shown in Fig. 9.

Figs. 16 and 17 are front view and side view respectively of the disk for imparting the step by step rotation of the mandrel shaft.

Figs. 18 and 21 illustrate the release mechanism for the driving shaft, while

Figs. 19 and 20 illustrate the mandrel shaft and plate holder.

Referring to Figs. 1 and 2 respectively of the appended drawings two systems of plotting on a square sensitive plate are shown. Plotting as shown by a' Fig. 1 has the advantage that it is never necessary to turn the camera to its side in order to obtain a change from the "landscape" (b Fig. 2) to the "portrait" (a Fig. 2) shape or proportion, while Fig. 2 involves turning the camera to its side when the change is required unless masking is adopted.

Let it be assumed that the lens is mounted opposite to b Fig. 2 and that a , b' , and a' are covered by an opaque mask, then the exposure will be on b and each of the four plate areas will come into position in due sequence as the plate or plate-system is made to rotate as hereinafter described.

Referring to Figs. 3, 4, 7, 10 and 11 of the drawings, 1 is the camera box having a hinged top 1 a , door 1 b and aperture 1 c . Mounted in bearings on a support or bracket 2 (Figs. 7 and 20) secured by screws 3 to the base of said camera 1 is a spindle f hereinafter termed the mandrel spindle, and integral therewith is a plate holder c . The plate is held in well known manner by the holder or carrier e (see Figs. 19 and 20). The mandrel spindle is also integral with a disk g (Figs. 3, 7, 8 and 20) and equally spaced apart around the disk g are four stops 4 (Fig. 8) by which it is locked into definite positions by the entry of the locking pin h (Fig. 3) into one of said stops 4. The means for operating the locking pin h is hereinafter referred to.

In front of the mandrel spindle and its allied parts is placed a partition 9, functioning as a mask, attached by screws 10 to the side of the camera box 1. This partition has an opening 11 (Figs. 3 and 4) to enable a plate area, e. g., a' when brought opposite the lens to be exposed as hereinafter referred to.

In front of the partition 9 is fixed a sup-

port 12 on which is mounted and fixed the lens or objective apparatus *r* of ordinary expanding type (see Figs. 10 and 11). The lens is centered so that its axis is directed 5 toward one of the four sections into which the plate is plotted for exposure.

The color screening is effected in well understood manner by a disk *n* fenestrated in four places, which disk is set in front of or 10 behind the lens or objective (see Figs. 3, 7 and 10), and this fenestrated disk (hereinafter called the screen holder) is made to rotate in quarter-circle stages in alternating correspondence with the quarter-circle stages 15 of the plate holder; the screen holder thus becoming an exposure shutter.

As shown in Figs. 3, 7 and 10 the screen holder *n* rotatably mounted in brackets 18 is set in front of the lens or objective. The 20 screen holder *n* has four openings 5, 6, 7 and 8 (Figs. 5 and 10) behind each of which openings is a sectorial cover *s* which can be adjusted so as to allow an appropriate illumination through each opening. As the 25 present invention is independent of or apart from any special aspect of color screening for multiple or composite heliochromy, it is not necessary to define the nature of the color screens to be used excepting to say 30 they should be in accordance with the known three color system and one exposure may be without a screen so that a print from the resulting negative may be used as a key in the assemblage of print elements. Further 35 a four color system may be used, or a two color system, in which latter case two heliochromes may be taken by one complete cycle of the apparatus.

The control and operation of the plate holder *g* mounted on the mandrel spindle *f*, and the screen holder *n* is by a shaft *j* mounted in brackets or standards 14, 14 (Figs. 3, 10 and 11) and parallel to that on 40 which the plate holder or carrier is mounted, this shaft (hereinunder called the driving shaft) having a tension of rotation communicated by a clock or other motor *i* (Fig. 11) of any convenient type, this tension of rotation being prevented from becoming 45 actual rotation by a catch or pawl 15, (see Figs. 3, 18 and 21) engaging a projection *l* on said shaft *j*, which may be freed at the will of the operator.

In Figs. 3 and 21 is shown a pneumatic 50 bulb *k* which when expanded releases the catch or pawl 15 from the projection *l* attached to the driving shaft *j* so as to allow this shaft to make one revolution under the drive of the clock *i*. The pneumatic bulb 55 *k* is of usual construction and on the other side to that of the catch or pawl 15, bears against a fixed stop 16. A flexible tube 60 16^a (Figs. 10 and 21) leads from the bulb *k* to the usual operating hand bulb or the 65 like 16^b (Fig. 10).

A driving disk *m*, (Figs. 12 and 13) on the driving shaft *j* is in even gearing (whether contact, tooth, band or chain) with the screen holder *n*.

On the driving shaft *j* and behind the disk *m* are two disks *p* and *o*, Figs. 16 and 17, the disk *p*, Figs. 14 and 15, controlling the periodical withdrawal of the pin *h* from one of the stops 4 on the disks *g*, and the disk *o* imparting the step by step rotation of 75 the mandrel shaft *f*. The disk *p* is provided with four projections *t* which press down the pivoted arm or stem *w* attached to the locking pin *h* (see Fig. 9) at appropriate times and thus withdraws the pin *h* from 80 the appropriate stop 4, and when the disk *g* is thus unlocked the mutilated gear of the disk *o* comes into operation on the disk *g* and brings the plate holder to a new position. The pin *h* is provided with a suitable spring 17 to bring it back into engagement 85 with the appropriate stop 4 in the disk *g*.

Instead of the driving shaft *j* being freed to make one complete revolution under the 90 drive of the motor it may be freed to have a range of action to make the camera self-acting for one complete stage of operations.

In operation assuming *b* Fig. 2 to be opposite the lens or objective *r* when the aforementioned catch or pawl 15 releases the projection *l* the driving shaft *j* rotates and the following movements are effected.

The disk *m* on the driving shaft *j* partially rotates the screen holder *n* so that 100 one fenestration for example 5, passes across the lens and makes an exposure on the area *b* of the plate.

The above mentioned exposure having 105 been made the two disks *p* and *o* on the driving shaft come into operation, the disk *p* by virtue of the appropriate projection *t* thereon withdrawing the pin *h* that during exposure locked the mandrel spindle *f* through the intermediary of the disk *g* and its stops 110 4 on the mandrel spindle. The mandrel spindle is now made to rotate one fourth of a circle by the mutilated gear *o* partially rotating the disk *g* fixed to the mandrel spindle *f*. Thus another plate area is brought 115 opposite to the lens and now the locking pin *h* again drops or springs into engagement with one of the aforesaid stops 4 on the disk *g*.

A second aperture or fenestration of the 120 screen holder now passes in front of the lens and the sequence of operations is repeated; there being in all four sequences.

The present invention furnishes an apparatus in compact form in which all adjustments are ready made or fixed and adapted 125 to the plates used so that complex adjustments are avoided.

Analyzing screens of known type may be 130 mounted immediately before the respective

plate areas in which case the rotary "screen holder" *n* would become merely an exposing shutter and a regulator of the light for the respective exposures.

5 As a modification rollers or spools may be provided on the plate holder or carrier, by which a band of sensitive film can be drawn over the face thereof.

Fig. 6 shows a plate holder or carrier *e* 10 on its mandrel spindle *f* and having two spools *u*, *u* mounted thereon a film *v* being shown as covering the surface of the plate holder *e*.

What I claim is:—

15 1. A camera for multiple or composite heliochromy, comprising a mandrel spindle, a face plate integral therewith, a carrier mounted thereon for a single color-sensitive surface plotted into exposure areas, lens or 20 objective apparatus in front of said color-sensitive surface, a screen holder, means for imparting step-wise rotation to the screen holder and to the mandrel spindle, and means for controlling said rotation.

25 2. A camera for multiple or composite heliochromy, comprising a mandrel spindle, a face plate integral therewith, a carrier mounted thereon, a color-sensitive surface carried thereby, lens or objective apparatus 30 in front of a unit-area of said color sensitive surface, a screen holder, means for imparting step-wise rotation to the screen holder and to the mandrel spindle and means for controlling said rotation.

35 3. A camera for multiple or composite heliochromy, comprising a mandrel spindle, a face plate integral therewith, a carrier mounted thereon for a single color-sensitive surface plotted into exposure areas, lens or 40 objective apparatus in front of said color sensitive surface, a screen holder, an expos-

ing shutter, means for imparting step-wise rotation to the shutter and to the mandrel spindle and means for controlling said rotation.

45

4. A camera for multiple or composite heliochromy, comprising a mandrel spindle, a face plate integral therewith, a carrier mounted thereon for a single color-sensitive surface plotted into exposure areas, a disk 50 integral with said mandrel spindle, a mask, and lens or objective apparatus in front of said color sensitive surface, a screen holder, a driving shaft, means for driving said shaft, means on said shaft for imparting 55 stepwise rotation to the screen holder and to the disk on the mandrel spindle, a controlling disk on the mandrel spindle, a catch operating thereon, releasing means on the driving disk for said catch, and means for 60 controlling the rotation of the driving disk.

5. A camera for multiple or composite heliochromy, comprising a mandrel spindle, a face plate integral therewith, a carrier mounted thereon, for a single color-sensitive 65 surface plotted into exposure areas, a disk integral with said mandrel spindle, a mask, and lens or objective apparatus in front of said color sensitive surface, a screen holder, adjustable openings therein, a driving shaft, 70 means for driving said shaft, means on said shaft for imparting stepwise rotation to the screen holder and to the disk on the mandrel spindle, a controlling disk on the mandrel spindle, a catch operating thereon, re- 75 leasing means on the driving disk for said catch, and means for controlling the rotation of the driving disk.

In testimony whereof, I affix my signature.

FRED JUDGE.
